[57] CLAIM

The ornamental design for a charger base for a battery-operated mixer, as shown and described.

DESCRIPTION

FIG. 1 is a front elevational view of a charger base for a battery-operated mixer showing my new design;

FIG. 2 is a right side elevational view thereof, the left side elevational view being a mirror image;

FIG. 3 is a rear elevational view thereof;

FIG. 4 is a bottom plan view thereof;

FIG. 5 is a top plan view thereof; and

FIG. 6 is a top front and right side perspective view thereof.

FIG. 1

FIG. 2

FIG. 3

FIG. 4

FIG. 5

FIG. 6
